UNITED STATES PATENT OFFICE.

ALFRED B. FOWLER, OF BEVERLY, MASSACHUSETTS, ASSIGNEE OF UNITED SHOE MACHINERY CORPORATION, OF PATERSON, NEW JERSEY, CORPORATION OF NEW JERSEY.

STOP MECHANISM.

Application filed October 25, 1919. Serial No. 333,275.

To all whom it may concern:

Be it known that I, ALFRED B. FOWLER, a citizen of the United States, residing at Beverly, in the county of Essex and State 5 of Massachusetts, have invented certain new and useful Improvements in Stop Mechanisms; and I do hereby declare the following to be a full, clear, and exact description of the invention, such as will enable others 10 skilled in the art to which it appertains to make and use the same.

The present invention relates to mechanisms for stopping a machine with the driven parts in a predetermined position, 15 and more particularly to stop mechanisms especially adapted for use in a machine wherein it is desirable to render certain parts or devices active for a predetermined interval during the final cycle of operations. A 20 machine of this type is the inseam shoe sewing machine illustrated and described in applicant's co-pending application, Serial No. 298,589, filed May 21, 1919, in which thread cutting and holding devices are employed 25 that are rendered active for a predetermined interval during the final cycle of operations of the machine.

The object of the present invention is to provide a novel and improved stop mechanism of the class above indicated, which is 30 relatively simple in construction and certain and reliable in operation.

With this object in view, the features of the present invention comprise certain constructions, arrangements and combinations 35 of parts hereinafter described and claimed, the advantages of which will be obvious to those skilled in the art.

The several features of the present invention will be clearly understood from the 40 following description and accompanying drawings in which: Figure 1 is a front elevation, partly in section, of a portion of a machine embodying the features of the invention in their preferred form; Figs. 2 and 45 3 are enlarged detailed sectional views taken on the lines 2—2 and 3—3 of Fig. 8, herein-after described; Fig. 4 is a vertical sectional view taken axially through the main shaft 50 of the machine and showing the stop mechanism in stopping position; Fig. 5 is a sectional view taken on the line 5—5 of Fig. 4 with a portion of the casing broken away; Fig. 6 is a view similar to Fig. 5 but with 55 the parts shown in the positions which they

assume during the normal operation of the machine; Fig. 7 is a plan view, partly in section, of the stop mechanism shown in stopping position; Fig. 8 is a view similar to Fig. 7 with additional parts in section 60 showing the position of parts of the mechanism during the final cycle of operations of the machine; Fig. 9 is a rear elevation, partly in section and with a portion of the casting removed, of the improved stop mechanism; Fig. 10 is a sectional view taken on the line 10—10 of Fig. 9; and Fig. 11 is a detail sectional view taken on the line 11—11 of Fig. 2.

In the drawings the invention is shown 70 embodied in a mechanism for driving and stopping a shaft 2 from which the operating parts of a sewing or other machine may be driven.

The illustrated stop mechanism includes 75 a high speed driving mechanism and a low speed driving mechanism. The high speed driving mechanism is adapted to drive the machine during the normal operation thereof, and the low speed driving mechanism is 80 adapted to be thrown in when the high speed driving mechanism is thrown out, and is designed to act first to reduce the speed of the machine and then to drive the machine at a low speed to stopping position. 85

The high speed driving mechanism comprises a continuously driven pulley 4 loosely mounted on the shaft 2, which pulley is adapted to be clutched to the shaft by the 90 engagement of a friction clutch face 6 on the interior thereof with a conical friction clutch face 8 on a clutch member 10 which is splined on the shaft.

The low speed driving mechanism comprises a spiral gear or worm wheel 12 which is journaled on a collar 14 secured to the shaft 2. The worm wheel 12 is continuously driven through speed reducing gearing from the high speed pulley 4. This gearing 100 comprises a spiral gear or worm 16, secured to the forward end of a counter shaft 18, which operatively engages the gear 12. On the rear end of said counter shaft is secured a spiral gear 20 which engages a spiral gear 105 22 carried by a counter shaft 24. A spur gear 26 is secured to the right end of the counter shaft 24 and is operatively engaged by a spur gear 28 secured by screws 30 to the pulley 4. The worm wheel 12 carries 110

a clutch member 32 having a conical friction clutch face 34 which is adapted to be engaged by a friction clutch face 36 on the clutch member 10. The worm wheel 12 also carries the driving member 38 of a one way positive roll clutch 40, the driven member of which comprises a sleeve 42 secured to the shaft 2. A pair of rolls 44 (Figs. 2 and 3) are interposed between said members of the clutch and are urged in a direction to clutch said members together by springs 46. The rolls are adapted to be shifted in the opposite direction to release the clutch by means of a rotatable ring 48 having lugs 50 extending longitudinally of the rolls, the ring 48 being thus actuated by means hereinafter described.

The clutch member 10 is urged towards the low speed clutch member 32 by means of springs 54 located in sockets in the member 10 and interposed between the inner ends of the sockets and a collar 56 formed on the driven shaft 2. The clutch member 10 is adapted to be shifted toward the pulley 4 by means of a collar 58 which is splined on the hub of the collar 14. The collar 58 actuates the clutch member 10 through sliding pins 60 and 61 which extend through apertures in the collar 14 and through slots 62 in the clutch ring 48. The pin 60 is provided with a cam surface 63 which is adapted to act on one side of its slot 62 so that when the collar 58 is shifted toward the right a sufficient distance, the clutch ring 48 will be rotated to release the roll clutch 40. The collar 58 is provided with an annular groove 64 which is engaged by studs or rolls on a forked arm 66 secured to a rock shaft 68. An arm 70 (Fig. 1) is secured to the forward end of the rock shaft 68 and the free end of this arm is connected by a rod 72 with a treadle mechanism (not shown) located at the base of the machine. When the rod 72 is depressed by means of the treadle mechanism, the arm 70 is swung downwardly which, through the rock shaft 68 and arm 66 shifts the collar 58 to bring the clutch member 10 into clutching engagement with the high speed pulley 4, whereupon the machine is driven at high speed. When the treadle rod 72 is released, a torsion spring 76 having one end connected to a lug 78 on the arm 66 and its other end connected to the frame of the machine, acts to shift the collar 58 to the left, whereupon the springs 54 are permitted to shift the clutch member 10 to throw out the high speed driving mechanism and immediately to engage the clutch member with the clutch member 32 of the low speed driving mechanism. The engagement of the clutch members 10 and 32 acts to reduce gradually the speed of the shaft 2 to that of the worm wheel 12, whereupon the worm wheel acts to

drive the shaft positively through the roll clutch 40. This movement of the collar 58 toward the left is limited by the engagement of a shoulder 79 on a stop lug 80 (Fig. 1), secured to the arm 70, with the lower end of a latch lever 82 pivoted on the frame of the machine. At a predetermined point in the rotation of the main shaft, a cam 84 carried by the clutch member 10 engages the upper end of the latch lever 82, whereupon, the lever is swung out of engagement with the lug 80 which permits the torsion spring 76 to shift the collar 58 into position so that its further rotation will cause a lug 86 formed thereon to engage a lug 88 on a controlling cam block 90. The cam block 90 is normally stationary and is loosely mounted on the main shaft. The engagement of the lug 86 with the lug 88 results in the cam block being carried in unison with the shaft 2 for a predetermined part of one revolution, whereupon the collar 58 is shifted to move the lug 86 out of engagement with the cam block. The cam block is held in this advanced position by the engagement of a lug 92 thereon with the upper end of a spring actuated latch lever 94 pivoted at 95 on the frame of the machine.

The movement of the collar 58 out of engagement with the cam block is accomplished by means of a plunger 96 mounted to slide in a bearing in the frame of the machine which engages a block 98 adjustably secured to the upper end of the forward fork of the collar shifting arm 66. The plunger is actuated by the engagement of a roll 100 on the left end thereof with a cam 102 carried by a hand wheel 104 secured to the end of the main shaft of the machine.

The foregoing described advancing movement of the cam block 90 may be utilized to render active certain parts or devices of the machine, in which the stop mechanism is embodied, for a predetermined interval during the final cycle of operations, for example, in the sewing machine illustrated and described in said co-pending application, a cam block corresponding to the cam block 90 is employed to release the brake connected with the tension wheel and to throw in the clutch which operates the thread cutting and holding devices.

At the completion of a predetermined number of degrees of rotation of the main shaft after the collar 58 is shifted out of engagement with the cam block, the collar is further shifted to the right a sufficient distance to release the roll clutch 40 of the low speed driving mechanism and to bring the clutch member 10 into neutral position. This additional movement of the collar 58 is accomplished by means of a plunger 106 mounted to slide in a bearing in the cam

block, which plunger engages the upper end 108 of the rear fork of the collar shifting arm 66. This plunger is actuated by the engagement of a roll 110 mounted on the 5 left end thereof with a cam 112 carried by the hand wheel 104. After the collar 58 is thus shifted by the plunger 106 to bring the clutch member 10 into neutral position, the collar 58 is held in this position, 10 until the driving mechanism is again thrown into operation by the operator, by a latch 114 (see Figs. 5, 6, 7 and 8) pivotally mounted at 91 on the cam block 90 and actuated upon by a spring 93, which latch moves 15 into a position to engage the adjustable block 98 as indicated in Fig. 7. When the machine is at rest, therefore, the main shaft is free from any driving or braking mechanism and can be rotated by hand by means 20 of the hand wheel 104 as may be desired.

It will be noted that when the treadle rod 72 is allowed to rise in stopping the machine the clutch mechanism is actuated to shift directly from the high to the low 25 speed drive and that this shift from the high to the low speed drive may occur at any point in the revolution of the main shaft. It will also be noted that this shift from the high to the low speed drive does 30 not immediately bring the controlling cam block 90 into operation but that the operation of the cam block is delayed until the main shaft has been driven by the low speed mechanism for at least a predetermined 35 interval. This result is accomplished by the provision of the latch 82 and the cam 40 84 by which it is actuated at a predetermined point in the rotation of the main shaft. The latch 82 can only be actuated 45 when the low speed drive is in operation and the engagement of the lug 86 on the clutch shifting collar 58 with the lug 88 on the cam block 90 occurs a certain and definite number of degrees of revolution 50 after the latch 82 has been operated. This insures a sufficient period of time between the throwing in of the low speed drive and the actuation of the controlling cam block to slow down the speed of the shaft to that 55 of the low speed drive so that the controlling cam block is actuated while the machine is being positively driven through the roll clutch at a comparatively slow speed. This action of the controlling cam block is thus rendered certain and reliable regardless of the speed at which the machine is run during its normal operation.

When the treadle rod 72 is depressed by the treadle mechanism to start the machine, 60 the lug 78 projecting from the lower end of the arm 66 engages an abutment screw 118 secured to the latch lever 94, thereby swinging the lever on its pivot to disengage the upper end thereof from the lug 92 on 65 the cam block 90. This allows a torsion

spring 120 having one end secured to the frame of the machine and its other end secured to the cam block to return the cam block to its initial position. This retracting movement of the cam block, which is in 70 a direction reverse to that of the rotation of the main shaft, is limited by the engagement of a lug 122 on the cam block with a yielding stop or buffer 124 on the frame of the machine. This buffer comprises a lug 75 126 projecting from the frame and a spring 126 having one end secured to the lug.

During the normal operation of the machine the operator by varying the amount of pressure on the treadle mechanism may 80 vary the degree of frictional contact between the clutch faces on the clutch member 10 and the high speed driving pulley 4 and thereby vary the speed of the machine. In the illustrated machine it is also possible 85 to throw in the low speed driving mechanism without bringing the lug 86 into a position to engage the lug 88, so that the machine may be driven during its normal operation by the low speed mechanism. 90 This may be accomplished by the operator releasing the treadle rod 72 only a sufficient amount to throw in the low speed mechanism and by maintaining the treadle rod in this position. By releasing the treadle 95 rod sufficiently to throw out the high speed mechanism without throwing in the low speed mechanism, the machine may be stopped by the resistance of its parts without throwing the cam block into operation. 100

The operation of the mechanism illustrated in the drawings has been indicated in connection with the description of the construction, but may be briefly summarized as follows: Starting with the parts at rest: 105 in the positions indicated in the drawings, a depression of the treadle rod 72 acting through the arm 70, rock shaft 68 and forked arm 66, will move the collar 58 to the right, as viewed in Fig. 4, and through the sliding pins 60 and 61 will force the clutch member 10 into engagement with the clutch face on the driving pulley 4. Through the pulley 4 and clutch member 10 the shaft 2 will be driven at high speed 110 until the treadle rod 72 is allowed to rise. The depression of the treadle rod 72 in starting the machine also releases the cam block 90 by moving the latch lever 94 out of engagement with the lug 92 and thereby allows the cam block to move to the position indicated in Fig. 6.

When the treadle rod 72 is released by the operator the collar 58 is shifted to the left, 115 as viewed in Fig. 4, a sufficient distance to permit the clutch member 10 to be moved by the springs 54 out of engagement with the driving pulley 4 and into engagement with the low speed driving member 32. By the action of the low speed driving 120 130

mechanism the speed of the shaft is first reduced and the shaft is then driven at the low speed. While the shaft is being driven by the low speed mechanism, the latch lever 32 is actuated by the cam projection 84 on the clutch member 10 to release the arm 70 and permit the collar 58 to be moved still further towards the left, as viewed in Fig. 4. After this movement of the collar 58 10 the continued rotation of the shaft 2 brings the lug 86 on the collar into engagement with the lug 88 on the cam block 90, and the block is moved from the position indicated in Fig. 6 to that indicated in Fig. 5, 15 in which position it is engaged and held by the latch 94. As the block 90 reaches the position indicated in Fig. 5, the collar 58 is shifted to the right, as viewed in Fig. 4, by the action of the plunger 96 and cam 20 102 on the hand wheel 104 to disengage the collar 58 from the block. Continued rotation of the shaft 2 causes an actuation of the plunger 106 by the cam 112 on the hand wheel 104 and through the plunger a further movement of the collar 58 to the right 25 sufficient to cause the sliding pins 60 and 61 to release the roll clutch between the low speed driving member and the shaft 2. The collar 58 is held in this position by the latch 30 114 on the cam block 90 until the treadle rod 72 is again depressed by the operator.

The nature and scope of the invention having been indicated and a machine embodying the several features of the invention in their preferred form having been 35 specifically described, what is claimed is:—

1. A stop mechanism having, in combination, a driven member, a high speed driving mechanism therefor, a low speed driving mechanism therefor comprising a friction clutch and a positive clutch, the friction clutch acting first to reduce the speed of the driven member to that of the low speed mechanism and the positive clutch then 40 acting to drive the driven member, and means for shifting from the high to the low speed driving mechanisms.

2. A stop mechanism having, in combination, a driven member, a high speed driving mechanism therefor, a low speed driving mechanism therefor comprising frictional and positive driving means acting first to reduce gradually the speed of the driven member to its own speed and then to drive 50 the driven member positively, and means for shifting from the high to the low speed mechanisms.

3. A stop mechanism having, in combination, a driven member, a high speed driving mechanism therefor, a low speed driving mechanism therefor, comprising cooperating friction clutch members for reducing the speed of the driven member, and means independent of said clutch members for then 60 driving the driven member, and means for

shifting from the high to the low speed driving mechanisms.

4. A stop mechanism having, in combination, a driven member, a high speed driving mechanism therefor, a low speed driving mechanism therefor comprising a friction clutch and a positive clutch, the friction clutch acting first to reduce the speed of the driven member to that of the low speed mechanism and the positive clutch then 70 acting to drive the driven member, and means for throwing both of said clutches into and out of operation.

5. A driving and stopping mechanism for a machine comprising a shaft and a controlling member for controlling the operation of parts of the machine having, in combination, high and low speed driving mechanisms for said shaft, means for shifting from the high to the low speed driving mechanisms, and means for rendering the controlling member active at least a predetermined interval after the low speed driving mechanism is thrown in.

6. A driving and stopping mechanism 90 for a machine comprising a shaft and a controlling cam for controlling the operation of parts of the machine having, in combination, high and low speed driving mechanisms, means for shifting from the high to the low speed driving mechanisms, and connections for rendering the controlling cam active at least a predetermined interval after the low speed driving mechanism is thrown in.

7. A driving and stopping mechanism for a machine comprising a shaft and a rotatable controlling member for controlling the operation of parts of the machine having, in combination, high and low speed 105 driving mechanisms, means for shifting from the high to the low speed driving mechanisms, and connections between the controlling member and the low speed driving mechanism for rotating the controlling member a predetermined number of degrees 110 a predetermined interval at least after the low speed driving mechanism is thrown in.

8. A driving and stopping mechanism for a machine comprising a shaft and a rotatable controlling member for controlling the operation of parts of the machine having, in combination, high and low speed driving mechanisms, means for throwing in the high speed driving mechanism and for shifting 115 from the high to the low speed driving mechanisms, connections between the controlling member and the low speed driving mechanism for rotating the controlling member a predetermined number of degrees a predetermined interval at least after the low speed driving mechanism is thrown in, and means rendered active upon throwing in the high speed driving mechanism for returning 120 the controlling member to its initial position.

100

105

110

115

120

125

130

9. A driving and stopping mechanism for a machine comprising a shaft and a controlling member for controlling the operation of parts of the machine having, in combination, high and low speed driving mechanisms, means for shifting from the high to the low speed driving mechanisms, for throwing out the low speed driving mechanism and for connecting and disconnecting the controlling member and the low speed driving mechanism to render the controlling member active and inactive, and means to insure that the controlling member shall be rendered inactive a predetermined interval before the low speed mechanism is thrown out. 70
10. A driving and stopping mechanism for a machine comprising a shaft and a controlling member for controlling the operation of parts of the machine having, in combination, high and low speed driving mechanisms, means for shifting from the high to the low speed driving mechanisms, for throwing out the low speed driving mechanism and for connecting and disconnecting the controlling member and the low speed driving mechanism to render the controlling member active and inactive, and means to insure that the controlling member shall be rendered active a predetermined interval after the low speed mechanism is thrown in, and rendered inactive a predetermined interval before the low speed mechanism is thrown out. 80
11. A driving and stopping mechanism for a machine comprising a shaft and a rotatable controlling member for controlling the operation of parts of the machine having, in combination, high and low speed driving mechanisms, means for throwing in the high speed driving mechanism and for shifting from the high to the low speed driving mechanisms, and connections between the controlling member and the low speed driving mechanism for rotating the controlling member a predetermined number of degrees while the low speed driving mechanism is thrown in, a latch for retaining the controlling member in the position moved, and means for releasing the latch and for returning the controlling member to its initial position upon throwing in the high speed mechanism. 90
12. A driving and stopping mechanism for a machine comprising a shaft and a rotatable controlling member for controlling the operation of parts of the machine having, in combination, high and low speed driving mechanisms, means for throwing in the high speed driving mechanism and for shifting from the high to the low speed driving mechanisms, a spring acting to rotate the controlling member in one direction, connections between the controlling member and the low speed driving mechanism for rotating the controlling member against the action of said spring a predetermined number of degrees while the low speed driving mechanism is thrown in, a latch for retaining the controlling member in position, and means for releasing the latch to permit said spring to return the controlling member to its initial position upon throwing in the high speed driving mechanism. 100
13. A driving and stopping mechanism for a machine comprising a shaft and a rotatable controlling member for controlling the operation of parts of the machine having, in combination, high and low speed driving mechanisms, means for connecting the controlling member and the low speed driving mechanism to rotate the controlling member after the low speed mechanism is thrown in, and means for disconnecting the controlling member and the low speed driving mechanism a predetermined interval thereafter. 110
14. A driving and stopping mechanism for a machine comprising a shaft and a rotatable controlling member for controlling the operation of parts of the machine having, in combination, high and low speed driving mechanisms, means for shifting from the high to the low speed driving mechanisms and for throwing out the low speed driving mechanism, means for connecting the controlling member and the low speed driving mechanism to actuate the controlling member after the low speed driving mechanism is thrown in, and means for disconnecting the controlling member and the low speed driving mechanism a predetermined interval before the low speed driving mechanism is thrown out. 120
15. A driving and stopping mechanism for a machine comprising a shaft and a controlling member mounted for rotation about the shaft having, in combination, high and low speed driving mechanisms for said shaft, a collar mounted to slide longitudinally of the shaft and interposed between the controlling member and members of the low speed driving mechanism, means for shifting from the high to the low speed driving mechanisms, for throwing out the low speed driving mechanism and for connecting and disconnecting the controlling member and the low speed driving mechanism, comprising said collar acting when shifted in one direction to connect the controlling member and the low speed driving mechanism and when shifted in the opposite direction to disconnect the controlling member and the low speed driving mechanism, 130

ing mechanism a predetermined interval thereafter to throw out the low speed driving mechanism.

16. A stop mechanism having, in combination, a shaft, high and low speed driving mechanism therefor, means for shifting from the high to the low speed driving mechanism, means acting automatically to disconnect the low speed driving mechanism and shaft, and means for maintaining such disconnection while permitting an independent rotation of the shaft.

17. A stop mechanism having, in combination, a shaft, high and low speed driving mechanism therefor, means for shifting from the high to the low speed driving mechanism, a cam and suitable connections for disconnecting the low speed driving mechanism and shaft, means for insuring at least a predetermined amount of slow speed drive before such disconnection, and means for maintaining such disconnection while permitting an independent rotation of the shaft.

18. A driving and stopping mechanism having, in combination, a shaft, high and low speed driving mechanism therefor, means for shifting from the high to the low speed driving mechanism and back to the high speed driving mechanism, means for

disconnecting the low speed driving mechanism and shaft, and means for ensuring at least a predetermined amount of low speed drive before such disconnection.

19. A driving and stopping mechanism having, in combination, a shaft, high and low speed driving mechanism therefor, mechanism for disconnecting the low speed driving mechanism and shaft to stop the shaft, treadle actuated connections for shifting from the high to the low speed driving mechanism and back to the high speed driving mechanism and for throwing said disconnecting mechanism into operation, and a cam actuated stop for said connections to time the throwing in of said disconnecting mechanism.

20. A driving and stopping mechanism having, in combination, a shaft, high and low speed driving mechanism therefor, means for disconnecting the low speed driving mechanism and shaft to stop the shaft, means for shifting from the high to the low speed driving mechanism and back to the high speed driving mechanism without throwing said disconnecting means into operation, and automatically acting means for throwing said disconnecting means into operation.

ALFRED B. FOWLER.
